[57] ABSTRACT

A new cultivar of *Forsythia intermedia* named 'Tinkle Bells' characterized by its floriferousness, its semi-dwarf, upright character, its downwardly directed flowers, and its leaves which are serrated only at their upper ends.

3 Drawing Sheets

1

This invention relates to a new cultivar of *Forsythia intermedia* named "Tinkle Bells", which is characterized especially by its semi-dwarf character, its upright growth habit, its pendulous flower buds and flowers, and the acute leaf tips on flowering wood foliage.

The new variety is a vegetative selection derived from a vegetative line of mutants, which had been produced in turn by subjected rooted cuttings of the parent *Forsythia intermedia* "Lynwood Gold" (*F. intermedia* "Spectabilis") to irradiation with 1,200 rad fast neutrons.

In 1968, three hundred cuttings of "Lynwood Gold" that had been potted and held in cold storage (38° F.) for six weeks and then returned to the greenhouse for two days were irradiated with 1200 rad fast neutrons. One of the plants of this group that broke dormancy formed a shoot with variegated foliage. This plant was cut back repeatedly to induce branching and eventually formed shoots that exhibited different characteristics. Each shoot was propagated by stem cuttings over 10 vegetative generations of selection and propagation. From this plant population two vegetatively selected types and three seedlings were selected. Further propagation and testing of these selections over several more years were shown to be the stable and new forsythia varieties that are the subject of this and four other co-pending plant patent applications; viz:

2

-continued

Ser. No.	Name	Type
271,666	"Pygmy-Red"	seedling

5 Each differs greatly from the parent "Lynwood Gold" and also from one another.

10 "Tinkle Bells" was selected from a group of vegetatively propagated shoots because it was very floriferous and attractive when in bloom. Cuttings from this plant have been rooted in soil and asexually propagated, and its progeny have displayed homogenous and stable characteristics.

15 Throughout this specification, color names beginning with a small letter signify that the name of the color as used in common speech are aptly descriptive. Color names beginning with a capital letter designate values based on the R.H.S. Colour Chart, published by The Royal Horticultural Society of London, England.

The accompanying drawings illustrate the new variety in color as grown in Knox County within the State of Tennessee.

20 FIG. 1 illustrates a five year old "Tinkle Bells" plant in spring bloom.

FIG. 2 shows flowered cut stems.

FIG. 3 is a close-up view of the flowers of FIG. 2.

25 FIG. 4 illustrates the "Tinkle Bells" plant in summer foliage.

FIG. 5 is a closer view of the foliage shown in FIG.

30 4. The following characteristics distinguish "Tinkle Bells" from its parent and other *Forsythia* cultivars:

Ser. No.	Name	Type
272,063	"Lemon-Screen"	vegetative selection
273,489	"Tinkle Bells"	vegetative selection
271,919	"Minikin"	seedling
271,665	"Fairy Land"	seedling

THE PLANT

Although "Tinkle Bells", like its parent "Lynwood Gold", exhibits an upright growth habit, the ultimate height of "Tinkle Bells" is 4 to 4½ ft. The plant exhibits medium vigor and is hardy in Zone 6b or lower. Because of its upright habit, "Tinkle Bells" tends not to self propagate by natural layerage, but the plant expands by stooling, i.e., shoots arise from the ground around the base of the plant, and the stooling can be controlled with post-emergence herbicides. Its upright growth habit and flowering at an early age make "Tinkle Bells" suitable for container growth and forcing. "Tinkle Bells" has a number of landscape applications, particularly for border and low screen plantings. The plant requires minimal pruning and has disease and insect-resistant foliage.

Its parent, "Lynwood Gold", by contrast is tall and slender—a straight upright variety with erect stems and which attains a height of 6 ft. to 7½ ft. at maturity.

SHOOTS

The stems of "Tinkle Bells" are yellow green when young and light brown when mature. The stems are rigid and the pith is sparsely lamellate between nodes.

The stems of the "Lynwood Gold" parent are green when young and brown when mature; they are a bit stiff; the pith at the nodes is lamellate, and on one year shoots, the stems between nodes are hollow.

FLOWER

"Tinkle Bells" flower early with bright yellow flowers (Yellow 7B) which generally have four, but occasionally five or six petals; the corolla is ½ inch long, opening up to approximately a 45 degree angle with a total spread of ½ in. to ¾ in. The pollen sacs of the stamen are located slightly below the stigmas of the short pistils. The plant generally produces two, but often four flowers per node on the flowering wood, which has internodes ½ to 1½ in. long. Both the buds and resultant flowers are pendulous on upright stems.

The "Lynwood Gold" parent is fertile and has pistils that extend well above its pollen sacs, is late flowering and its medium sized flowers (about 1" to 1½" in diameter) are almost evenly spaced on the stem. The flowers of "Lynwood Gold" are brilliant yellow (lighter than its parent, *F. spectabilis*). The corolla lobes of "Lynwood Gold" are reflexed and its petals are large, broad open and elliptic.

FOLIAGE

The "Tinkle Bells" leaves are medium green both in the young and mature stage. The leaves are simple elliptical, generally serrate, but only on the upper one-third, near the tip. The leaves are acute on flowering shoots and acuminate on vegetative shoots. The leaves are ½ in. wide and, including the petiole, are 2 in. to 3 in. long.

The leaves of the "Lynwood Gold" parent, on the other hand, are ovate lanceolate in shape and about 3" to 4½" long and about 1" to 1½" wide. Both young and old leaves are deep green in color.

To facilitate the comparison of the characteristics and features of "Tinkle Bells", the subject of this application, and its parent, "Lynwood Gold" and also with the four other new mutant offspring varieties of "Lynwood Gold" referred to above, there are attached hereto as Tables 1-5 comparative tabulations of the characteristics and properties of parent and its five offspring mu-

tants that were developed from a single irradiated plant of "Lynwood Gold." Table 1 compares "Tinkle Bells" and its parent "Lynwood Gold". Table 2 compares "Tinkle Bells" and "Pygmy-Red". Table 3 compares "Tinkle Bells" and "Lemon-Screen". Table 4 compares "Tinkle Bells" and "Minikin". Table 5 compares "Tinkle Bells" and "Fairy Land".

TABLE 1

S/N 273,489		
TINKLE BILLS		LYNWOOD GOLD
<u>Plant:</u>		
Habit	Semi-dwarf; Upright	Tall, slender-Upright straight & erect stems
Size, height	4-4½'	6-7½'
Size, width		
Vigor	Medium vigor	
Hardiness	Hardy Zone 6b (or lower)	
Productivity	Does not layer naturally (replicates from stools (no seed pods observed)	Fertile
<u>Stems:</u>		
Color (young)	Yellow Green	Green
Color (mature)	Light brown	Brown
Rigidity	Sparsely lamellate between nodes - Rigid	A bit stiff; pith nodes lamellate; hollow between nodes on one year shoots
<u>Leaves:</u>		
Type	Simple	
Color:		
(young)	Medium green	Deep Green
(mature)	Medium green	Deep Green
(fall)	Faded green to yellow	
Shape	Elliptical	ovate lanceolate
tip	Acute on flower shoots acuminate on vegetative shoots	
base		
margins	serrate on upper ½ near tip	
<u>Size:</u>		
length	2"-3" (with petiole)	3-4½"
width	½"	1-1½"
Venation	Pinnate	
Flower:		
Date of	Early	Late
Flowering		
Size: width	½"-¾" at 45° angle	1"-1½" (medium)
Color:	Bright Yellow (7 B)	Brilliant Yellow (Lighter than its parent Spectabilis)
<u>Corolla:</u>		
length	½" open to 45° angle not reflexed during prime	Reflexed
lobes		
Petals: number	4; occasionally 5 or 6	Large, broad, open
Pistils:	short: anthers slightly below stigma portion of pistil	Elliptic
Number per node:		Extend well above
Insertion angle	2; often 4 per node	pollen sacs (anthers) of stamens
on upright stems:	buds & flowers pendulous	
Internodes:	½"-1½"	
Stress Resistance:		Flowers almost evenly spaced on stems
Utility Aspects:	Disease and insect Can force flowering suitable for container culture	

TABLE 2

	S/N 273,489 TINKLE BELLS	S/N: 271,666 PYGMY RED
<u>Plant:</u>		
Habit	Semi-dwarf; Upright	Low, loose graceful arching to ground
Size, height	4'-4½'	3½'-4½'
Size, width		5'-6'
Vigor	Medium vigor	Good vigor
Hardiness	Hardy Zone 6b (or lower)	Hardy Zone 6b (or lower)
Productivity	Does not layer naturally (replicates from stools (no seed pods observed)	Readily roots where branches touch ground few seed pods
<u>Stems:</u>		
Color (young)	Yellow Green	High anthocyanin
Color (mature)	Light brown	Purple Red (39 A)
Rigidity	Sparingly lamellate between nodes - Rigid	Flexible lamellate between nodes
<u>Leaves:</u>		
Type	Simple	Simple
<u>Color:</u>		
(young)	Medium green	Dark Green
(mature)	Medium green	Dark Green
(fall)	Faded green to yellow	Anthocyanin (maroon) expressed in full sun
Shape	Elliptical	Lanceolate (few lobed leaves on vegetative shoots)
tip	Acute on flower shoots accumulate on vegetative shoots	Accuminate
base margins	serrate on upper ½ near tip	Attenuate Serrate
<u>Size:</u>		
length	2"-3" (with petiole)	2"-2½" on flowering wood; to 2½" on vegetative wood
width	½"	0.3"-0.4" on flowering wood; to 1" on vegetative wood
<u>Venation Flower:</u>	Pinnate	Pinnate
Date of Flowering	Early	Intermediate
Size: width	1"-3" 45° angle	2"-2½" on flowering wood; to 2½" on vegetative wood
Color:	Bright Yellow (7 B)	Yellow (7A)
<u>Corolla:</u>		
length lobes	½" open to 45° angle not reflexed during prime	Narrow
Petals: number	4; occasionally 5 or 6	4 - sometimes 5
Pistils:	short: anthers slightly below stigma portion of pistil	Extend 2/25"-3/25" above pollen sacs of stamens
Number per node:	2; often 4 per node	2
Insertion angle on upright stems:	buds & flowers pendulous	1"-1½"
Internodes:	1"-1½"	1"-1½" (1½" even on fast growing shoots)
Stress Resistance:	Disease and insect	disease and insect
Utility Aspects:	Can force flowering suitable for container culture	

TABLE 3

	S/N 273,489 TINKLE BELLS	S/N 272,063 LEMON SCREEN
<u>Plant:</u>		
Habit	Semi-dwarf; Upright	Tall, open and graceful; Upright, fan shape; vigorous; open foliage
Size, height	4'-4½'	Up to 10'
Size, width		Hardy Zone 6b (or lower)

TABLE 3-continued

	S/N 273,489 TINKLE BELLS	S/N 272,063 LEMON SCREEN
5	Vigor	Medium vigor
	Hardiness	Hardy Zone 6b (or lower)
	Productivity	Does not layer naturally (replicates from stools (no seed pods observed)
10	<u>Stems:</u>	Abundant Flowers/ highly sterile/pruned wood branches quickly
	Color (young)	Yellow Green
	Color (mature)	Light brown
	Rigidity	Sparingly lamellate between nodes - Rigid
15	<u>Leaves:</u>	Yellow
	Type	Simple
	<u>Color:</u>	Simple
	(young)	Medium green
	(fall)	Faded green to yellow
	Shape	Elliptical
20	tip	Acute on flower shoots accumulate on vegetative shoots
	base	Accuminate
	margins	serrate on upper ½ near tip
25	<u>Size:</u>	Attenuate
	length	2"-3" (with petiole)
	width	½"
	Venation	Pinnate
	Flower:	Pinnate
	Date of Flowering	Early
30	Size: width	1½"-2" 45° angle
	Color:	Bright Yellow (7 B)
	<u>Corolla:</u>	1½" open to 45° angle not reflexed during prime
35	length lobes	Somewhat reflexed
40	Petals: number	4; occasionally 5 or 6
	Pistils:	short: anthers slightly below stigma portion of pistil
	Number per node:	2; often 4 per node
	Insertion angle on upright stems:	buds & flowers pendulous
45	Internodes:	1"-1½"
	Stress Resistance:	Disease and insect
50	Utility Aspects:	Can force flowering suitable for container culture

TABLE 4

	S/N 273,489 TINKLE BELLS	S/N 271,919 MINIKIN
<u>Plant:</u>		
Habit	Semi-dwarf; Upright	Small stature, fine textured; small leaves and small stems; densely foliated
Size, height	4'-4½'	2"-2½"
Size, width	3'-4'	Good vigor but slow growth
Vigor	Medium vigor	Zone 6b (or lower)
65	Hardiness	Hardy Zone 6b (or lower)
	Productivity	Does not layer naturally (replicates
		Abundant seed pods

TABLE 4-continued

	S/N 273,489 TINKLE BILLS	S/N 271,919 MINIKIN	
<u>Stems:</u>			
Color (young)	Yellow Green	Light green	
Color (mature)	Light brown	Brownish green	
Rigidity	Sparsely lamellate between nodes - Rigid	Ascending strongly lamellate between nodes	
			5
<u>Leaves:</u>			
Type	Simple	Simple	
<u>Color:</u>			
(young)	Medium green	Bright green to dark green	
(mature)	Medium green	Bright green to dark green	
(fall)	Faded green to yellow	Fading green until leaf drop	
Shape tip	Elliptical Acute on flower shoots acuminate on vegetative shoots	Linear Accuminate	
base margins	serrate on upper $\frac{1}{2}$ near tip	Attenuate Lightly serrate	
<u>Size:</u>			
length	2"-3" (with petiole)	On vegetative shoots- $1\frac{1}{2}$ " attached to $\frac{1}{2}$ " long slender petiole; smaller on flowering shoots	
width	$\frac{1}{4}$ "	On vegetative shoots - $\frac{1}{4}$ "; Pinnate	
Venetion Flower:	Pinnate		
Date of Flowering	Early	Intermediate	
Size: width	$\frac{1}{4}" - \frac{3}{8}"$ 45° angle	$\frac{1}{4}" - \frac{3}{8}"$ (cup shaped) fully reflexed	
Color: Corolla:	Bright Yellow (7 B)	Yellow (9 A)	
length lobes	$\frac{1}{4}"$ open to 45° angle not reflexed during prime	strongly reflexed, very small	
Petals: number	4; occasionally 5 or 6	4: short and recurved	
Pistils:	short: anthers slightly below stigma portion of pistil	Short; 1/25" below pollen sacs of stamens	
Number per node:	2; often 4 per node	2-4	
Insertion angle on upright stems:	buds & flowers pendulous	Short (Flowering shoots $\frac{1}{4}" - \frac{3}{8}"$ Vegetative shoots up to 2")	
Internodes:	$\frac{1}{4}" - 1\frac{1}{2}"$	Doesn't require same degree of winter protection as most container grown plants of genre	
Stress Resistance:	Disease and insect	Blooming can be forced. Especially suited for container culture.	
Utility Aspects:	Can force flowering suitable for container culture
